Primary Examiner — Mary Ann Calabrese(74) *Attorney, Agent, or Firm* — Santosh K. Chari; Blake, Cassels & Graydon LLP(57) **CLAIM**

The ornamental design for a sign for a shelf, substantially as shown and described.

DESCRIPTION

FIG. 1 is a perspective view of a sign for a shelf according to our new design.

FIG. 2 is a front elevational view of the design of FIG. 1.

FIG. 3 is a rear elevational view of the design of FIG. 1.

FIG. 4 is a left elevational view of the design of FIG. 1.

FIG. 5 is a right elevational view of the design of FIG. 1.

FIG. 6 is a top view of the design of FIG. 1; and,

FIG. 7 is a bottom view of the design of FIG. 1.

The shading shown in the figures serves to illustrate transparency and is not surface ornamentation.

The portions of the figures shown in broken lines represent features that do not form part of the claimed design.
